UNITED STATES PATENT OFFICE

100,208

DESIGN FOR A WASHING MACHINE OR THE LIKE

Clark A. Depue, Clinton, Iowa, assignor to The Maytag Company, Newton, Iowa, a corporation of Delaware

Application March 26, 1936, Serial No. 61,799

Term of patent 7 years

To all whom it may concern.

Be it known that I, Clark A. Depue, residing at Clinton, in the county of Clinton and State of Iowa, a citizen of the United States, have invented a new, original, and ornamental Design for a Washing Machine or the Like, of which the following is a specification, reference being had to the accompanying drawing forming a part thereof.

The figure is a perspective view of a washing machine or the like showing my new design. The dominant feature of my design resides in the portions shown in full lines.

I claim:

The ornamental design for a washing machine or the like substantially as shown and described.

CLARK A. DEPUE.
